PACKAGE AND DISPENSER FOR GUMMED TAPE

Filed Dec. 10, 1926

Inventor
Irving McHenry
By Williams, Bradbury,
Mc Caleb & Hinke

UNITED STATES PATENT OFFICE.

IRVING McHENRY, OF RIVER FOREST, ILLINOIS, ASSIGNOR TO MID-STATES GUMMED PAPER CO., OF CHICAGO, ILLINOIS, A CORPORATION OF ILLINOIS.

PACKAGE AND DISPENSER FOR GUMMED TAPE.

Application filed December 10, 1926. Serial No. 153,767.

My invention relates to dispensing containers for gummed paper, being concerned more particularly with the provision of a novel enclosing and dispensing package for 5 gummed paper tape, which package is adapted to be sold with a roll of gummed paper tape to serve as a dispenser therefor. While I am aware that many devices have been made for dispensing and moistening gummed 10 tape, all of these devices include very complicated mechanism having moving parts, cutting knives, etc., for severing the tape, together with complicated moistening devices, and the cost of such dispensers is obviously 15 too great to permit the sale or gift of a dispenser with each roll of tape that is sold.

One of the objects of my invention is the elimination of the difficulties incident to the manufacture of such complicated dispensing 20 devices and the provision of a dispenser having no relatively moving parts.

Another object of my invention is the provision of a package container and dispenser for gummed tape which is simple in construction and can be so cheaply manufactured 25 that it may be sold with a small portion of gummed tape, in order to be used as a container and dispenser for the tape.

Another object of my invention is the provision of a dispensing container for gummed 30 tape, including means for moistening the tape, means for severing the tape, means for retaining the tape in position in the container spaced from said moistening device 35 and means for permitting access to the tape to withdraw and moisten the same.

Further objects and advantages of my invention will appear more fully in the following detailed description and from the accompanying drawings, in which similar characters 40 of reference indicate similar parts throughout the several views.

Figure 1 is an elevational view in cross section along the line 1—1 of Figure 2;

Figure 2 is a plan view of the bottom of 45 the cover shown in Figure 1; and

Figure 3 is a view in perspective of the cover of Figure 1 with the tape removed.

Referring to Figure 1, 10 indicates in its 50 entirety a container for gummed tape, comprising a substantially rectangular box-like

member 11, preferably formed of cardboard, a thin sheet metal cover 12, and a bottom 13, preferably formed of thin sheet metal. The bottom 13 may be secured to the side walls 11 55 by providing a stamped rectangular groove 14 which is upwardly and inwardly crimped as at 15 about the bottom edge of the cardboard walls 11.

The cover 12 comprises a substantially rectangular cover adapted to fit upon the cardboard walls 11, having a flat central portion 16 which may be stamped inward as at 17 to a plane slightly lower than the outer edge 18 of the cover and having a flange 19 adapted 60 to fit closely about the cardboard walls 11. The cover 12 is provided with a plurality of slits 20, 21 and 22 of slightly greater length than the width of the gummed tape 23, a roll 65 of which, 24, is shown within the container 10.

In forming the slits 20, 21 and 22, all of which may be done in a single stamping operation, the portion 25 of the cover between the slits 20 and 21 is stamped downward forming 75 a flat table 25 supported by side flanges 26 at a plane slightly below the flat central portion 16 of the cover 12, and at the same time the end of the flat table 25 adjacent the slit 20 is downwardly turned as at 27 to form a 80 curved guide, more readily permitting the insertion of the tape into the slit 20. The table 25 should be sufficiently offset below the flat portion 26 so that the tape may enter at the slit 20 and pass in a straight line across the table 25 underneath the flat portion 16 85 out of the slit 22. The edge 28 of the slit 22 upon the flat portion 16 forms a sharp edge for severing the tape by pulling upward upon either side of the tape and the opposite edge 90 29 of the slit 22 may be downwardly bent to form a curved flange to guide the tape 23 downward through the slit 22.

The cover 12 is also provided with an aperture 30 extending across the cover a distance 95 slightly greater than the width of the slits 20 and 21 and the gummed tape 23, and the aperture 30 may be bounded by a pair of downwardly turned flanges 31 and 32 at right angles to the plane 16 of the cover 12.

In order to form a guide for the gummed 100 tape 23 and a support for a moistening device

33, further to be described, I provide a thin stamped metal plate 34 having a flat rectangular portion 35 extending from beneath the table 25 to the flange 29, a downwardly curved flange 36 fitting against the end of the flange 29, a flat portion 37 extending from the flange 29 to the flange 31 and a well 38. The well 38 may be formed by bending the metal piece 34 downwardly at right angles at 39 forming a semi-circular curve 40 and an upwardly extending flange 41 of slightly greater length than the flange 39, in such manner that the flanges 39 and 41 fit outside the flanges 31 and 32 and the upper end of the flange 41 may be outwardly turned as at 42 to fit below the cover 12. The flat portion 35 of the metal piece 34 may be bent upward at each side with a narrow flange as at 43 in such manner that the flanges 43 may fit about the flanges 26 which support the table 25, and also the flanges 43 may form side walls for the guide between the flat portion 16 and the plate 35. It will thus be observed that the space 44 is a substantially rectangular tube-like member adapted to guide the gummed tape 23, through the same out of the slit 22.

In addition to the foregoing, the cover 12 may preferably have a plurality of metal tabs 45 stamped out of its surface at each end for the purpose of securing the metal plate 35 beneath the cover 12, and the metal plate 35 is preferably formed with a plurality of inward cuts 46 at each end, adapted to receive the tabs 45, forming shoulders on both sides of said tabs to retain the plate 35 in position, when the tabs 45 are bent upward against said plate.

The well 38 is provided with a small piece of absorbent felt of such width and thickness as will conveniently fit within the aperture 30 and having the top edge cut at a bevel of 45° or more to form a widened top surface 47 which is adapted to be bent over upon the cover 12 to more effectively moisten the tape 23. It will be noted that the upper tip 48 of the felt pad 33 may be compressed between the upper surface of the cover 12 and the tape 23 in the operation of drawing the tape over the pad 33, thereby bringing the water to the surface of the felt pad 33, and that besides increasing the effective area of the felt pad 33, the beveled construction provides a point 48 which will perform this useful function. Another advantage of the beveled construction is that the forward edge 53 of the absorbent pad 33 being at or slight below the surface of the cover 15, when the tape 23 is slid outward by sliding the thumb upon the portion 52, the end 51 will not be caught upon the pad 33, as would be the case in the usual type of felt pad, but the beveled surface 47 will deflect the end 51 upward and over the point 48, thus facilitating the projection of the end 51 beyond the tip 48, where it can be grasped by the thumb and forefinger. After

the tape 23 has been torn off at the edge 28, the point 48 is relieved from compression against the cover 12 and resumes the position shown in Figure 1 during which the moisture in the pad 33 tends to become evenly distributed throughout the pad 33.

It will be observed that while the well 38 may be made waterproof if so desired, I prefer, in order to make a simple and cheap structure, to form the same of a single supporting flange having no end pieces, as the felt pad 33 need not contain sufficient moisture to drip out from below the well 38.

The operation of my dispensing device is as follows:

The roll of tape 24 is disposed within the dispenser 10, being loosely contained within the same, so that the tape may unroll as it is pulled from the container. In order to provide sufficient frictional resistance with the simple structure I have devised, I roll the gummed tape with its adhesive layer to the outside as at 49, passing the end of the tape in at the slit 20 around the flange 27, across the table 25, in at the slit 21, through the guide 44, out at the slit 22 between the edge 28 and the flange 29. By rolling my tape in the manner described, I secure an arrangement of the roll of tape within the container producing a sharp bend at the point 50 where it passes over the curved flange 27, and the friction provided by this bend and the guide 44 is sufficient to retain the tape in position in the slits and guides when the end of the tape is torn off at the edge 28.

When it is desired to use the tape for pasting objects of any kind together, such as fastening paper packages, mending music, labeling jars, etc. the felt pad 33 is removed, moistened with water, slightly squeezed to remove the excess water, and replaced in the well 38, as shown in Figure 1. The end 51 of the tape 23 would then be at the edge 28 where it was last torn off, and unless means were provided for access to this end, it would be impossible to grasp the same to withdraw the tape. I provide such means in the form of a table 25 upon which the tape 23 is exposed as at 52, and by pressing the thumb against the tape 52 adjacent the slit 20 and sliding the thumb toward the slit 21, the tape 52 will be progressively urged out of the slit 22, where it may be grasped between the thumb and forefinger and pulled across the felt pad 33 moistening the tape. The location of the table 25 with the exposed portion of the tape 52 is particularly advantageous in the present construction, because the act of pulling out and moistening the tape may be made in a single motion by sliding the thumb on the paper 52 across the plane surface 16, then grasping the end 51, pulling the paper across the felt pad 33. The desired length of tape is then severed by pulling sidewise against the edge 28, as previously described,

and it will be observed that the balance of the tape is adequately held within the guide 44 and the container 10, with the tape spaced from the moistening device so that it cannot 5 become sticky or adhere to the container. The flanges 27 and 29 as well as the side flanges 43 of the guide 44 are very effective in permitting the insertion of the tape through the slits 20, 21 and 22 in the first 10 operation of filling the container.

It will thus be observed that I have provided a very simple, economical construction, which may be so cheaply manufactured that the dispenser may be sold with a small roll 15 of tape for home, office, or school use and that my combined package and dispenser has no relatively moving parts to get out of order.

While my dispenser is particularly adapted 20 for use in small packages of the kind described, I desire it to be understood that my invention is of general application and that it may also be used with larger packages of 25 gummed paper or fabric of all kinds. While I have illustrated and described a specific 30 embodiment of my invention, many changes may be made without departing from the spirit of the invention, and I do not desire to be limited to the specific details of the construction set forth but desire to avail myself of all changes within the scope of the appended claims.

Having thus illustrated and described my invention, what I claim is new and desire to 35 secure by Letters Patent of the United States is as follows:

1. In a gummed paper dispenser, a box-like container adapted to receive a roll of 40 tape and a cover for the same comprising a stamped sheet metal cover having a plurality of slits therein, a flat portion of said cover depressed between the first and second of said slits, a flat piece of metal secured in spaced 45 relation to said cover below said slits to form a guide for said tape and a moistening device supported in said cover.

2. In a gummed paper dispenser, a box-like container adapted to receive a roll of tape, a cover for the same comprising a stamped 50 sheet metal cover having a plurality of slits therein, a flat portion of said cover depressed between the first and second of said slits, a flat piece of metal secured in spaced relation to said cover below said slits to form a guide for said tape and a downwardly turned flange 55 adjacent the third of said slits to guide said tape outwardly and a moistening device supported in said cover.

3. In a gummed paper dispenser, a box-like container adapted to receive a roll of 60 tape and a cover for the same comprising a stamped sheet metal cover having a plurality of slits therein, a flat portion of said cover depressed between the first and second of 65 said slits, a flat piece of metal secured in

spaced relation to said cover below said slits to form a guide for said tape, said cover having an aperture spaced from said third flange, and a moistener support formed by the end of said flat piece beneath said aperture.

4. In a gummed paper dispenser, a box-like container adapted to receive a roll of tape and a cover for the same comprising a stamped sheet metal cover having a plurality of slits therein, a flat portion of said cover depressed 70 between the first and second of said slits, a flat piece of metal secured in spaced relation to said cover below said slits to form a guide for said tape, said cover having an aperture spaced from said third flange, a moistener support formed by the end of said flat piece beneath said aperture, and a beveled piece of absorbent felt supported in said aperture. 75

5. In a gummed paper dispenser, a box-like container adapted to receive a roll of 80 tape and a cover for the same comprising a stamped sheet metal cover having a plurality of slits therein, a flat portion of said cover depressed between the first and second of said slits, a flat piece of metal secured in spaced 85 relation to said cover below said slits to form a guide for said tape, said cover having an aperture spaced from said third flange, a moistener support formed by the end of said flat piece beneath said aperture, and a plurality of tabs struck from said cover and bent 90 about said flat piece. 95

6. In a gummed paper dispenser, a box-like container adapted to receive a roll of 100 tape, a cover for the same comprising a stamped metal cover having a plurality of slits therein, a downwardly flanged rectangular aperture, a flat metal plate supported in spaced relation under said cover and having a moistener support formed in one end thereof, said moistener support engaging the flanges of said aperture, and a plurality of tabs punched from said cover to be bent about 105 said plate, and shoulders on said plate on each side of said tabs. 110

7. In a gummed paper dispenser, a box-like container adapted to receive a roll of tape, a cover for the same comprising a stamped metal cover having a plurality of slits therein, a downwardly flanged rectangular aperture, a flat metal plate supported in spaced relation under said cover and having a moistener support formed in one end thereof, said moistener support engaging the flanges of said 115 aperture and a beveled piece of absorbent felt in said aperture. 120

8. In a gummed paper dispenser, a box-like container adapted to receive a roll of tape, a cover for said container comprising a stamped sheet metal covering having a plurality of slits through which the tape may be passed, the cover between the first and second of said slits being depressed to provide a thumbing surface for advancing the tape, and said cover having a downwardly turned 125 130

flange on one side of the third of said slits to retain the same in assembled relation with
for guiding the tape, a guide comprising a strip of sheet metal extending between the
second and third of said slits and engaging said flange, said strip also having a moistener reservoir formed therein, said cover having a plurality of lugs bent over said strip to retain the same in assembled relation with
said cover, and said cover having a flanged aperture adjacent said moistener reservoir. 10
In witness whereof, I hereunto subscribe my name this 7th day of December, 1926.

IRVING McHENRY.
